ROCK DRILLING EQUIPMENT

Alexander Cameron, Walkerville, Newcastle-upon-Tyne, England, assignor to Victor Products (Wallsend) Limited

Application April 9, 1951, Serial No. 220,067

Claims priority, application Great Britain

April 26, 1950

6 Claims. (Cl. 255—53)

This invention relates to equipment for rotary rock drilling particularly for use in underground workings, or for preliminary work in tunnel driving. It is further concerned with so-called manual force feed appliances for drilling holes in rock faces. By manual operation it is found that in drilling such holes, particularly in hard rock faces, a single workman or indeed two workmen operating jointly cannot steadily apply the necessary pressure required in a hand drill. In force feed working therefore, the reaction pressure due to the feeding of the drill is sustained by a prop, and the drill is supported by a feed spindle or bar along which the drill is propelled. The object of the invention therefore, is to provide a manual drilling installation which is convenient to set up, and in which the convenience and ease of operation are increased as much as possible, and the invention particularly aims at such an installation in which flanking holes can be drilled around a given point in the rock face without fresh settings, and in which manipulations for inserting rods of successively increasing lengths can be effected in the simplest and promptness of fashions.

According to the present invention, a drilling equipment is set up on a fixed rear prop to which the drill and its support are pivoted in such a way that it can be operated at angles slightly inclined to the horizontal so that holes can be drilled above and below the horizontal line with a single setting. The feed spindle or bar is made extensible so that by the simple manipulation a steady at the forward end of the feed spindle or bar can be readily brought into engagement with the rock face either on the horizontal line or at points on either side of it.

In order that the invention may be clearly understood and readily carried into effect, an example of a force feed equipment for rock drilling in accordance with the present invention, will now be more fully described with reference to the accompanying drawings, in which—

Figure 1 is a side elevation of the equipment; Figure 2 is a plan of the same with the rear prop shown in section on the line II—II in Figure 1;

Figure 3 is a side elevation to an enlarged scale of the steady point of the feed bar and its spring, shown partly in central section;

Figure 4 is a detailed rear elevation seen in the direction of the arrow IV in Figure 2;

Figure 5 is a central vertical longitudinal section showing the forwarding mechanism and the registering device for the feed bar, to an enlarged scale;

Figure 6 is a vertical transverse section taken on the line VI—VI in Figure 5; and

Figure 7 is an enlarged elevation partly in section of the ratchet handle for the feed bar forwarding mechanism.

Referring particularly to Figures 1 and 2, the drilling equipment is set up on a rear prop 1 which, in the example illustrated, consists of an outer steel tube 2 provided with a spiked foot-plate 3 and an inner telescoping bar 4 fitted with a spiked roof plate 5. The bar can be raised or lowered by a handle 6 which rotates a pinion engaging rack teeth 7 on the bar 4. Thus the plates 3 and 4 can be forced into engagement with the floor and roof of the working and the prop 1 firmly secured. The pinion may be locked in the adjusted position by a locking pawl brought into engagement with the pinion by a finger piece 8.

20 The feed bar 9 is supported near its rear end in a tubular mounting 10 which is pivoted on a stout pivot pin 11 which extends to one side from a clamp 12 which embraces the outer tube 2 of the prop 1. The clamp 12 is a ring in two halves

25 12a, 12b which are forced together to grip the prop 1 by a clamping screw 13 turned by a short handle 14. The tubular mounting 10 has an upwardly extending bracket plate 15 which has an aperture to pass over the pivot pin 11 and to bed against a seating 16 on the back of the clamp 12. This arrangement enables the mounting 10 and the feed bar 9 to be turned to an angle to the horizontal plane when it is desired to drill holes above or below the centre line of the clamp 12. The mounting 10 and feed bar 9

30 35 are secured in the desired angular position by a long cap nut 17 rotated by a handle 18 and screwed on to the outer threaded part 19 of the pivot pin 11.

The feed bar 9 extends rearwardly through the tubular mounting 10, and immediately in front of the latter is another tube 20 connected to the back of the feed bar 9 by a parallel key or feather 21 so that the feed bar 9 can slide in the tube 20, but when the latter is rotated the feed bar 9 is turned with it. The rear end of the tube 20 is formed with a flange 22 shown in contact with the front end of the housing 10. The tube 20 supports in bearings a pinion 23 in engagement with the teeth 24 of the rack bar 9. The spindle 25 of the pinion 23 has squared ends 26 to receive a removable crank handle such as is seen at 27 in Figure 1 and Figure 7, and contains a one-way or ratchet clutch comprising ratchet teeth 28 formed on its boss and a pawl 29 slidable in

50 55 the handle and pressed by a compression spring

30 into engagement with the ratchet teeth 29, so that by rocking the handle 27 to and fro as shown by the arrow 31 in Figure 7, the pinion 23 can be rotated. It is arranged for the pinion 23 to be locked from backward rotation by a spring pressed pawl 32 shown in Figure 5 pressed into engagement by a sliding plunger 33 pressed forward by a spring 34. However, the locking pawl 32 can be withdrawn by swinging over the handle 35 to the position shown in broken lines in Figure 5 when the spring 34 holds the pawl in the disengaged position. By this means the tube 20 can be pressed back against the tubular mounting 10 and by continuing to rotate the pinion 23 the feed bar 9 can be racked forwardly to cause a steady pin 36, seen in Figures 1, 2 and 3, to engage the rock face 37, whereupon the pawl 32 is engaged and prevents the feed bar 9 from moving away from the rock face 37.

As best seen in Figure 3, the steady pin 36 is carried at the forward end of a stem 38 which can slide in a bore 39 at the front end of the feed bar 9, and the steady pin 36 is pressed forwardly by a strong coiled compression spring 40 engaging under the head of the pin 36 and against the front of the feed bar 9. However, as the latter is moved forward and pressed against the rock face 37 as already described, the spring 40 is compressed and holds the pin 36 against the rock face. The stem 38 is guided by a set screw 41 engaging a key way 42 in the stem 38, and incidentally limits the stroke of the stem 38 and prevents the spring 40 from entirely ejecting the steady pin from the bore 39 in the feed bar 9. The drill proper 43 (Figure 1) is held in a chuck 44 mounted on the driving shaft 45 in the front of the drill housing 46. The shaft 45 and drill 43 may be driven by an electric motor carried in the housing 46 through suitable reducing gearing, the electric motor being supplied through a trailing cable 47. The drill housing 46 is supported by a pair of lugs 48 secured to a tube 49 connected by a parallel key or feather 50 to the feed bar 9. Behind the housing 46 is a tube 51 also connected to the feed bar 9 by a parallel key or feather 52 so that both the motor housing 46 and the tube 51 can slide along the feed bar 9 but are constrained to rotate with the latter. The tubular housing 51 supports a pinion and spring controlled locking pawl, as already described for the tube 20. The squared ends of the pinion spindle 53 appear at 53a and are engaged by the handle 27 which is of the construction already described and can be rocked as indicated by the arrow 54 in Figure 1. By making the parts of the tubular housings 20 and 51 and the driving mechanism carried by them identical, the number of necessary different parts is reduced and the same crank handle 27 used for pressing the feed bar 9 forward can also be used for pushing forward the tubular housing 51 and (thereby, feeding the drill 43 into the rock, since the two operations of course never have to be conducted together. It will be appreciated that while the pinion 23 has to be rotated counter-clockwise, that on the spindle 53 has to be turned clockwise. This, however, can be effected by the same handle 27 as the direction of drive can be reversed merely by taking off the handle 27 and turning it back to front before replacing it.

The feed bar 9 can be rotated in the tubular mounting 10 but when so rotated it causes the tubes 20 and 51 and the motor housing 46 to turn with it, and as the drill 43 is off-set from the axis of the feed bar 9 it means that the drill can be

turned to drill holes in various positions on a circle around the axis of the feed bar 9. In order to secure the drill in any one of these drilling positions, the flange 22 of the tubular mounting 10 is formed with a number of radial notches 55 (Figures 4 and 5), which are intended to be engaged by a latch 56 which is pivoted about a transverse pivot 57 passing between lugs 58 which stand up from the tubular mounting 10, so that when the feed bar 9 is turned into one of the desired positions the latch 56 is turned by a handle 59 into engagement with the corresponding notch 55 and then locks the feed bar 9 in the desired angular position. In the example illustrated there are only four notches 55 shown mutually at right angles so as to provide four angular positions for drilling, but obviously a greater number of notches may be provided in the flange 22 if conditions demand it.

The drill rods or tools 43 can clearly be changed rapidly without disturbing the general setting up of the equipment, for example if a hole has been drilled with a three foot drill rod 43, this rod can be uncoupled at the chuck 44, the handle 27 removed and, with the locking pawl in the housing 51 disengaged, the drill housing 46 with the tube 51 can be quickly drawn back, the drill rod 43 withdrawn from the hole in the rock face and a longer drill rod inserted in its place. The drill housing 46 is brought forward again and the longer drill rod 43 coupled up to the chuck 44 ready for further drilling.

I claim:

1. A rotary rock-drilling equipment comprising in combination, a fixed supporting prop, a tubular mounting secured to said prop, a drill feed bar formed with rack teeth and mounted to slide in said tubular mounting, a rock-engaging steady pin resiliently mounted at the forward end of said feed bar, a first pinion meshing with the rack teeth of said feed bar and journaled to thrust against said mounting when rotated to press said feed bar forwardly, a drilling unit supported on said feed bar and mounted to slide thereon to and from said rock-face, a second pinion meshing with the rack teeth of said feed bar and journaled to feed said drilling unit forwardly when rotated and a ratchet handle formed to engage alternatively each of said pinions to rotate the respective pinions in one direction.

2. A rotary rock-drilling equipment according to claim 1, also comprising a sleeve splined to said feed bar and located immediately in front of said tubular mounting and formed with bearings for said first pinion and a second identical sleeve splined to said feed bar and located immediately to the rear of said drill unit but reversed with respect to said first-named sleeve and formed with bearings for said second pinion.

3. A rotary rock-drilling equipment according to claim 2, also comprising manually-operated means for locking said first pinion against rotation.

4. A rotary rock-drilling equipment according to claim 1, wherein said feed bar is mounted for rotatable adjustment in said tubular mounting and said drilling unit is splined to said feed bar and bears a drill chuck offset from said feed bar so that the drill chuck acquires a fresh setting on adjustment of said feed bar and said drilling unit, said equipment having means for maintaining said feed bar in adjusted position.

5. A rotary rock-drilling equipment comprising in combination a fixed supporting prop, a tubular mounting secured to said prop, a drill

feed bar mounted for rotatable adjustment in said mounting, a sleeve adjacent to said mounting and splined to said feed bar and rotatably adjustable therewith, a drilling unit splined to said feed bar so as to slide thereon to and from the rock face to be drilled and bearing a drill chuck offset from said feed bar so as to acquire a fresh setting on adjustment of said feed bar in said mounting, locking means carried by said sleeve and said mounting, engageable to maintain said sleeve and feed bar in selected angular adjustment with respect to said tubular mounting and means for feeding said drilling unit along said feed bar towards said rock face.

6. A rotary rock-drilling equipment according to claim 5, wherein said locking means comprises a notched flange coaxial with said sleeve and a

transversely pivoted latch engageable with the notches of said flange to maintain said sleeve in a definite angular adjustment with respect to said tubular mounting.

ALEXANDER CAMERON.
